UNITED STATES PATENT OFFICE.

HANNAH M. NEIDIG, OF SUNBURY, PENNSYLVANIA.

GARMENT-FASTENING.

No. 825,551.

Specification of Letters Patent.

Patented July 10, 1906.

Application filed January 16, 1906. Serial No. 296,276.

To all whom it may concern:

Be it known that I, HANNAH M. NEIDIG, a citizen of the United States, residing at Sunbury, in the county of Northumberland and State of Pennsylvania, have invented new and useful Improvements in Garment-Fastenings, of which the following is a specification.

This invention relates to improvements in garment-fastenings, and more especially to placket-fasteners.

It is also adapted to secure waists in place by securing them to skirts and performs a double function of a waist-retainer and skirt-supporter.

It is simple in construction, readily attached to the garment, quickly operated, and entirely out of sight when in use.

The various features of the invention will be hereinafter more fully explained and described in connection with the accompanying drawings, in which—

Figure 1 shows the fastener attached to a placket of a skirt, the placket thrown open. Fig. 2 shows the fastener attached to a waist, the skirt-band turned down. Fig. 3 is a view of the fastener attached to a skirt with the placket closed looking from opposite side of Fig. 1. Fig. 4 is a section on line 4 4 of Fig. 3.

Referring to the drawings, 1 indicates the left side of a skirt-placket looking from the rear, with the eyes 2 each made of a single piece of wire, sewed on the skirt.

3 indicates the right side of a skirt-placket. A indicates a fastener embodying my invention, consisting of a single piece of wire having a straight body portion 4 and end portions 4^a bent at right angles to the body portion, said end portions terminating in

loops or thread-eyes 6. Near each end portion the wire is doubled closely upon itself, forming hooks 5, which project laterally from the body. These hooks have their central portions 7 bent out of line with their end portions, as shown in Fig. 4, forming humps which assist in preventing the disengagement of the hooks from the eyes 2. Midway between the hooks the wire has a part 8 doubled upon itself and forming a loop which

projects laterally from the body portion. The end portions 4^a, the hooks 5, and the loop 8 all project in the same direction from the body of the fastener. The fastener is secured to the garment by sewing through the thread-eyes 6, the loop 8, and around the entire body portion and end portions. When

sewed to the garment, all of the lateral projections lie flat against the garment except the hump portions of the hooks. The end portions and the central loop being sewed fast to the garment and projecting in the same direction as the hooks prevent the latter from swaying or moving outward away from the garment when a stress in that direction is put upon the hooks by the eyes on the opposing part of the garment. The eyes 2 are of common form, consisting of short pieces of wire bent in their central portions and provided with eyes at their ends, as shown. It will be noted that when the hooks engage the eyes they extend between the central parts of the eyes and the cloth to which the eyes are attached, and the ends of the hooks lie flat against the part of the garment to which the hooks are attached. When the two parts of the garment are pulled in opposite directions, it will be seen that the eyes pull against the ends of the hooks adjacent to their points of connection with the body of the fastener, so that ordinarily there is little tendency to turn or bend the hooks. The ends of the hooks lie flat against the garment and are not liable to catch on any other part of the clothing.

Fig. 2 shows the fastener applied to a waist adapted to engage eyes on the waistband of a skirt. By this arrangement the waist is always held in place and the skirt is prevented from sagging, thus performing the double function of retaining the waist in place and supporting the skirt.

9 is an ordinary single hook on the waistband of a skirt which engages the eye 10 and is used in conjunction with the double hook 5. The form of fastener described may be used in pairs—that is, one to fasten the placket and the other to secure the waist in place and support the skirt. Its advantages over other fasteners are that it is easily operated, does not catch other parts of garments when in use, does not buckle and show a ridge, is invisible, and is cheaply manufactured. The eyes are all large, which admits of slight movement of the hooks when the body assumes different positions, but the hooks cannot become dislodged.

Having described my invention, what I claim, and desire to secure by Letters Patent, is—

1. A garment-fastener consisting of a single piece of wire doubled closely upon itself near each end, said doubled portions project-

ing laterally to the main or body portion of the wire and forming hooks, said wire also having a part near its center doubled upon itself to form a loop extending laterally from the body portion, and the ends of the wire being also bent laterally, said hooks, loop and end portions projecting in the same direction from the body portion, and said end portions having eyes at their extremities.

10 2. A garment-fastener consisting of a single piece of wire doubled closely upon itself near each end, said doubled portions projecting laterally to the main or body portion of the wire and forming hooks, said wire also

having a part near its center doubled upon itself to form a loop extending laterally from the body portion, and the ends of the wire being also bent laterally, said hooks, loop and end portions projecting in the same direction from the body portion, and said hooks having their central portions bent out of line with the ends of the hooks, to form humps.

In testimony whereof I affix my signature in presence of two subscribing witnesses.

HANNAH M. NEIDIG.
